R. W. BROWN

METHOD AND APPARATUS FOR HEATING A LIQUID

Filed August 17, 1923

UNITED STATES PATENT OFFICE.

ROY W. BROWN, OF AKRON, OHIO, ASSIGNOR TO THE FIRESTONE TIRE AND RUBBER COMPANY, OF AKRON, OHIO, A CORPORATION OF OHIO.

METHOD AND APPARATUS FOR HEATING A LIQUID.

Application filed August 17, 1923. Serial No. 657,994.

This invention relates to a heating apparatus and particularly to an apparatus for heating water or other fluids.

The invention is herein shown as embodied in an apparatus for heating water for use in a tire vulcanizing apparatus in which the tires are subjected to external and internal heat and pressure, but the invention in many of its features is not limited to use in connection with apparatus of this type.

It has been proposed, heretofore, to cure pneumatic tires upon a water filled bag in preference to the cast iron cores commonly used, the water serving as a medium to carry heat to the inner layers of the tire, as well as supplying the necessary internal pressure. Many difficulties have arisen, however, in the use of the water cure, due chiefly to variations in temperature of the water when it enters the tires, and the inability of known apparatus to preclude against such variations.

A general object of this invention is to provide a heating system in which water will be raised to the desired temperature and automatically maintained thereat until its entrance into the tires.

A further object of this invention is to provide a heating apparatus in which water may be raised to extremely high temperatures in an efficient and economic manner.

In a further aspect the invention provides a novel method of producing super-heated water.

These and other features of the invention and the novel method referred to will appear more fully from the following detailed description when read in connection with the accompanying drawings and will be pointed out in the appended claims.

In the accompanying drawings, an example of the invention is shown in operative combination with a tire vulcanizer, it being understood that this is for the purpose of description and illustration only and without any intent to define the limits of the invention.

In the drawings is shown a side elevation of the heating apparatus selected to illustrate the preferred embodiment of the invention.

Referring to the drawings, the letter A designates as a whole the device in which the water is initially heated, and B a second heater used to superheat the water, referred

to hereinafter for convenience as a preheater 55 and after-heater respectively, while C denotes the vulcanizing chamber in which the tires are cured in a manner well known to those skilled in the art.

The preheater A consists of a water pipe 2 arranged in any suitable number of coils 4 and surrounded by a steam jacket 6 of standard construction. The steam jacket is connected by a pipe 8 to a main steam line, shown at 10. A pipe 12 connected at one end to the steam jacket at 14 and at the other to a steam trap 16 conducts the steam from the steam jacket in a manner clearly understood.

From the preheater A the water is conducted to the after-heater B by a conveying pipe 18 connected to the water pipe 2 by a short pipe 20, the pipe 18 communicating with the bottom of the after-heater. The after-heater B is substantially cylindrical in shape and contains a water chamber 22. The bottom 24 of the heater B is elevated above the floor by means of a supporting block 26 to facilitate the attachment of the water pipe 18. Within the heater B is arranged a spiral coil 28 through which the heating medium, preferably steam, is conducted. The upper end of the coil 28 is connected to a pipe 30 extending through the top 32 of the heater, the pipe 30 forming an extension of the main steam supply line 10. The lower end of the coil 28 extends through the bottom of the heater and is connected by a pipe 34 to a steam trap 36. Within the heater B are arranged any number of baffle plates 38, three being shown, the top and bottom plate being provided with a central opening 40 and the middle plate with side openings 42, the effect of the plates being to cause the water to flow in a zigzag path through the heater.

Extending through the top of the heater B and communicating with the water chamber 22 therein is a pipe 44 forming part of the conduit line between the heater and the vulcanizing chamber C. The pipe 44 is connected to a distributing pipe 46 within the vulcanizing chamber by a cross pipe 48 which extends through the top of the vulcanizer. The distributing pipe 46 is built up of a number of short lengths which are connected by any standard form of coupling T 48, each T being located opposite a mold 50. In each T is inserted a connecting tube 52 having on

its opposite end a nozzle by which the tube 52 can be connected to the interior of a tire enclosed within the mold 50.

The pipe 48 is connected by a short pipe 54 to a vacuum line by means of which the air may be withdrawn from the tires prior to the insertion of the water therein, thus avoiding the formation of air pockets and "cold spots" in the tire.

10 The novel means for controlling the temperature of the water and maintaining it at a constant temperature until its introduction into the tires will now be described.

15 A temperature controller 56 is provided to automatically control the temperature of the water in the preheater A. To this end the controller is connected by a tube 58 to a diaphragm valve 68 suitably placed along the steam inlet pipe 8. Extending within 20 the water outlet pipe 20 is a thermostatic bulb 70 connected to the controller through a capillary tube 72. The controlling instrument is of standard construction and a detailed description thereof is not necessary. 25 Suffice it to say that when the temperature of the water as it flows past the thermostatic bulb varies from a predetermined point, the controller 56 will cause the operation of the diaphragm valve 68 to open or close the 30 amount necessary to bring the water entering the heater to the desired temperature.

It will be appreciated, however, that a temperature controlling system of this type will not maintain the temperature of the 35 water always constant, a condition which this invention is designed to bring about. This is due largely to the fact that the water within the heater at the time of the operation of the controller will not be affected by the increase or decrease in the flow 40 of steam, and, therefore, will not be brought to the predetermined temperature.

Located at a convenient point along the water pipe 18 is a circulating pump 74 through which the water flows on its way to the after-heater B. The circulating pump is driven at a constant speed and serves to force the water through the after-heater at a predetermined velocity.

50 A second controlling instrument 76, similar in construction and operation to the controller 56, is provided for controlling the temperature within the after-heater B. A diaphragm valve 78 is provided in the steam inlet pipe 30, the valve being operated by the instrument through a tube 80. A capillary tube 82 extends from the instrument 76 to the afterheater and is provided with the usual thermostatic bulb 84 extending 55 through an opening 86 into the water chamber 22. The bulb 84 is so positioned in the length of the water chamber that variations in the temperature of the water from the desired point as it passes the bulb will be corrected by the time the water reaches the top

of the heater, due to the fact that the water is flowing at a predetermined speed, and the amount of steam turned on will be sufficient to bring the water to the proper temperature by the time it has traveled the distance from the bulb to the top of the heater, the speed of the water and the distance traveled being constant.

In order to withdraw the water which remains in the heater above the thermostatic bulb after the tires have been filled for one vulcanization and which, of course, will cool off by radiation, a pipe 90 is attached to the outlet pipe 44 near the point of juncture of the latter with the pipe 48. The pipe 90 extends downwardly and connects with the pipe 18, from which the water therein is again forced through the after-heater by the circulating pump 74.

85 Suitable check valves 92 and 94 are provided in the pipes 20 and 90 respectively to keep the water flowing in the proper direction through the circuit.

90 While the operations of the component parts of the heating system have been set forth in the foregoing description, they may be summarized briefly as follows:

In passing through the preheater A, the water is raised to a temperature approximately that finally desired. In the after-heater the water is superheated and raised to the exact temperature required, being retained thereat by the circulating pump and the controlling instrument 56. Therefore, when the water enters the vulcanizing apparatus it has a uniform temperature throughout, a prerequisite to the production of an even and thorough cure of the inner layers of the tire.

100 Having described my invention, what I claim as new and desire to secure by Letters Patent of the United States is:

1. In a device of the class described, the combination of two independent heating units, means for conducting a fluid through the said units, and temperature controlling devices for automatically controlling the temperature of the liquid in each unit.

2. In a device of the class described, having in combination, two independent heating units, means for conducting a liquid through each unit successively, and means for automatically raising the liquid to a predetermined temperature before it leaves the second heater.

115 3. In a device of the class described, having in combination, two independent heating units, means for conducting a liquid in a continuous stream through the heaters, means for automatically controlling the temperature of one of said heaters, and means for raising the fluid to a constant temperature before it leaves the other heater.

125 4. A device of the character described having in combination, two independent

heating units, means for conducting a fluid directly through one of said units, and means for circulating the water continuously through the other.

5. A device of the character described having in combination, a heating unit, means for conducting a fluid through the unit, means for automatically controlling the temperature of the heating unit, a second heating unit, means for conducting the liquid from the first heating unit through the second, and means controlled by the temperature of the water at one point in the second heater for bringing the liquid to a constant 10 temperature before it leaves the said second heater.

6. A device of the character described, having in combination, two independent heating units, means for conducting a liquid through each unit in succession, and means for forcing the liquid through one of said heaters at a constant speed.

7. A device of the character described, having in combination, two independent heating units, means for conducting a liquid through each of said units in succession, means for forcing the liquid through one of said heaters at a constant speed, and means controlled by the fluid for bringing the fluid 20 to a constant temperature before it passes through the said heater.

8. A device of the class described, having in combination, a steam coil, means for conducting a liquid through the coil, means for automatically controlling the temperature of the said coil, a heating chamber, a pipe for conducting the liquid from the coil to the heating chamber, a circulating pump connected with said pipe, means for raising 30 the temperature of the liquid to a constant temperature before leaving the heating chamber, means for conducting the liquid from the chamber, and means for leading some of the fluid back to the circulating 40 pump.

9. A process of heating a liquid comprising conducting the liquid through two heating units, and returning some of the liquid to one of the heaters.

50 10. A process of heating a liquid comprising conducting the liquid through a heating unit, leading the liquid to a second heating unit, and forcing the liquid through the second unit at a constant speed.

55 11. A process of heating a liquid comprising heating the liquid, leading the heated liquid to a heating chamber, forcing the liquid through the chamber at a constant speed, and returning some of the liquid to the heating chamber.

60 12. A process for vulcanizing rubber articles comprising conducting a fluid through

two heating units, returning some of the fluid to one of said units and passing the fluid from said unit about said articles. 65

13. A process for vulcanizing rubber articles comprising conducting a liquid through one heating unit, leading the liquid to a second heating unit, forcing the liquid through the second unit at a constant speed and 70 passing the liquid from said second unit about said articles.

14. A process for vulcanizing rubber articles comprising heating a liquid, leading the liquid to a heated chamber, forcing the 75 liquid through the chamber at a constant speed, returning some of the liquid to the chamber and passing the liquid from said chamber about said articles.

15. A process for vulcanizing rubber articles comprising preheating a liquid while controlling the temperature thereof to be substantially uniform and adjacent the temperature required for vulcanization of said articles, further heating said liquid while 80 separately controlling its temperature to be substantially uniform and at the temperature required for vulcanization of said articles, and leading said liquid about said articles. 90

16. A process for curing tires on water bags, comprising preheating a supply of liquid to adjacent the temperature of vulcanization while maintaining said temperature uniform within a comparatively wide range 95 of variation, further heating said liquid to the temperature of vulcanization while maintaining said temperature uniform within a comparatively narrow range of variation and supplying said liquid to said water 100 bags.

17. Apparatus for the class described comprising, in combination, a vulcanizer, means for supplying a curing medium to the vulcanizer, a preheater through which the curing medium is first conducted, means for controlling the temperature of the medium delivered from said preheater, an after-heater through which the medium is conducted, and means for controlling the temperature of the medium delivered by the after-heater to said vulcanizer. 105

18. Apparatus for vulcanizing rubber articles comprising the combination with a vulcanizer and means for supplying a curing fluid thereto of a preheater adapted to heat said fluid approximately to curing temperature, an after-heater for further heating said fluid, and means for controlling said after-heater so that fluid delivered thereby will 115 be accurately and uniformly maintained at a required temperature of vulcanization. 120
